(57) **CLAIM**

The ornamental design for an actuation handle, as shown and described.

DESCRIPTION

FIG. 1 is a top perspective view of an actuation handle showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines form no part of the claimed design.
